CURTAIN RAISING AND LOWERING FIXTURE

Ida Lundstrom, St. Louis, Mo.

Application December 29, 1947, Serial No. 794,360

4 Claims. (Cl. 211—103)

1

This invention relates to curtain fixtures and more particularly to a fixture embodying elements designed to support a curtain that can be raised and lowered with, or without a curtain supported thereby.

A further object of the invention resides in the provision of a curtain fixture that can be raised and lowered by means of pull-cords, thus avoiding possible accidents that occur when standing on chairs, stools, or the like.

I carry the invention into practice by providing an arrangement of parts designed especially for dependable coordination to enable the curtain fixture to be easily and quickly raised or lowered with, or without a curtain, in a dependable manner when standing on the floor.

Other objects and advantages of the invention relate to various details of construction and novel arrangement of parts as will be more fully set forth in the following specification, illustrated in the accompanying drawings and defined in the appended claims.

In the accompanying drawings:

Fig. 1 is a front elevation, partly in cross-section, of a fixture embodying the features of my invention, the same being shown in full lines in its raised position, and shown in dotted lines in its lowered position.

Fig. 2 is a plan view of the fixture.

Fig. 3 is a side elevation of the fixture in its raised position and partly shown in sectional elevation.

Fig. 4 is a front elevation of one of the carriers.

Fig. 5 is a front elevation of the other carrier.

Fig. 6 is a horizontal sectional view taken on line 6—6 of Fig. 5.

Fig. 7 is a plan view of one of the pull-cord supporting members.

Fig. 8 is a plan view of the other pull-cord supporting member.

Fig. 9 is a modification of one of the pull-cord supporting members.

In the drawing, the reference character 1 designates a conventional illustration of the upper portion of a window frame.

Suitably secured to the window frame 1 adjacent the upper corners thereof are supporting members, or elements designated, generally as 2 and 3. The members 2 and 3 each consist of a suitable fastening element such, for instance as a screw 4, or similar element and they are provided with suitably shaped heads 5 and 6 of plastic, or metallic material. Head 5 is provided with a suitable vertical cord passage 7, and head 6 is provided with a pair of suitably spaced, vertically disposed cord passages designated 8 and 9.

A suitable flexible pull-cord 10 is threaded downwardly through and rides in the cord passage 7 of head 5. The cord 10 spans the gap between the heads 5 and 6 and is threaded downwardly through and rides in the cord passage 9 of the head 6.

A suitable flat plate like carrier 11 of plastic or metal and preferably rectangular in shape, is

2

suspended from the end of the cord 10 below the supporting member 2 therefor. The carrier 11 is provided with a pair of vertically aligned openings 12 and 13 arranged adjacent the upper and lower edges thereof and through which the pull-cord 10 is threaded so as to lie on the back face of the carrier, and the free end of the pull-cord 10 is suitably anchored in the lower carrier opening 13. The cord section on the back face of the carrier protects the carrier from riding in contact with the face of one of the side members of the window frame 1, thus avoiding damage thereto.

A suitable flexible pull-cord 14 is threaded downwardly through and rides, or slides in the cord passage 9 of head 6.

A suitable flat plate like carrier 15 of suitable plastic, or metallic material and preferably rectangular in shape, is suspended from the end of the cord 14 below the supporting member 3 therefor. The carrier 15 is provided with a pair of vertically aligned openings 16 and 17 adjacent the upper and lower edges thereof and through which the cord 14 is threaded so as to lie on the back face of the carrier and the free end of the carrier is suitably anchored in the lower carrier opening 17. The cord section on the back face of the carrier protects the carrier from riding in contact with the face of the other side member of the window frame 1, thus avoiding damage thereto when sliding up and down thereon in raising and lowering the carriers, in unison, by means of the pull-cords. The pull-cord 14 is directed downwardly over the side of the head 6 as it leaves the upper end of the cord passage 9.

Both pull-cords 10 and 14 pass downwardly from the head 6 and pass through spaced loops 18 and 19, respectively carried by the carrier 15 intermediate its ends which space and guide the cords relative to the front face of the carrier 15.

Both pull-cords pass downwardly from the loops 18 and 19 and at a selected position below the carrier 15, a spacer 20 is adjustably connected to the cords 10 and 14.

The pull-cords continue downwardly a suitable distance from the spacer 20.

A suitable member 21 is secured to the side member of the window frame 1 at a suitable elevation, preferably within the reach from the floor, around which the cords can be wound for holding the carriers in their uppermost positions in upper edge contact with the lower faces of the heads 5 and 6 or at any desired elevation therebelow. Thus, the heads 5 and 6 will limit upward movement of the carriers suspended from the pull-cords 10 and 14, and the spacer 20 will limit downward movement of the carriers 11 and 15 by coming into contact with the carrier 15 adjacent the loops 18 and 19 which serve as stops for the spacer 20 limiting upward movement thereof.

Suitable telescopically connected curtain supporting sections 22 and 23, made either from plastic or metallic material, are suitably carried at their outer ends by the upper portions of the carriers 11 and 15. The carriers 11 and 15 preferably project downwardly a suitable distance from

the lower edges of the curtain supporting sections 22 and 23.

The pull-cord supporting member 3 shown in Fig. 9 is shown as provided with grooved cord passages 8' and 9' instead of the circular openings 8 and 9, as shown in Fig. 8.

Operation of the fixture

Assuming that the carriers and curtain supporting sections are in their uppermost position, the upper edges of the carriers 11 and 15 contact the lower faces of the pull-cord supports 2 and 3, respectively, and are held in their position by twisting the pull-cords around the member 21 secured to the window frame. In this position of the fixture, the carriers lie parallel with the face of the window frame, with the cord sections on the backs of the carriers lying in contact with the face of the window frame.

Now, when it is desired to lower the carriers and curtain supporting sections, the operator releases the cords from the member 21 and the weight of the fixture will cause the same to be lowered by gravity the desired distance. The spacer 20 will limit downward movement of the fixture by coming into contact with the lower end of the carrier 15 adjacent the loops 18 and 19. The carriers 11 and 15 will be lowered together and in unison, thereby holding the curtain supporting sections in a horizontal position.

To raise the carriers 11 and 15 and the curtain supporting sections carried thereby, it is only necessary to pull on the pull-cords until the carriers contact the lower faces of the pull-cord supporting members 2 and 3, after which the pull-cords are tied to the member 21 secured to the window frame 1.

The many advantages of the herein described invention will readily suggest themselves to those skilled in the art to which it appertains.

Various minor changes and modifications will be readily apparent to those skilled in the art to which the invention relates and are contemplated within the purview of the appended claims, therefore it is understood that the above particular description and drawings are by way of illustration and example only, and that changes, omissions, additions, substitutions, and/or modifications might be made within the scope of the claims without departing from the spirit of the invention which is intended to be limited only as required by the prior art.

What I claim is:

1. A curtain fixture comprising a pair of supporting members adapted to be secured to a window frame adjacent the upper corners thereof, pull-cords slideable through vertical openings in said supporting members, vertically movable carriers suspended from like ends of the pull-cords, loops carried by one of the carriers through which the two pull-cords pass downwardly, a spacer secured to the pull-cords, telescopically connected curtain-rod sections connected at their outer ends with the carriers, said pull-cord supporting members serving as stops to limit upward movement of the carriers, the spacer serving as a stop to limit downward movement of the carriers by coming into contact with the lower end portion of the loop provided carrier, and means adapted to be secured to a window frame a suitable distance below the loop provided carrier to which the pull-cords are detachably connected to hold the carriers in their uppermost positions and in contact with the lower faces of the pull-cord supporting member.

2. In a fixture of the class described, a pair of elements having pull-cord passages adapted to be secured to a window frame adjacent the upper corners thereof, a pair of pull-cords adapted to ride in the passages of said elements, a pair of telescopically connected curtain-rod sections, a carrier connected to the outer end of each curtain-rod section, pull-cord receiving loops carried by one of the carriers, said carriers being secured to and suspending from like ends of the pull-cords below the aforesaid elements for up and down movement by respectively pulling on and releasing the pull-cords, upward movement of the carriers being limited by coming into contact with the aforesaid elements, a spacer carried by the pull-cords below the loop provided carrier which serves to limit downward movement of the carriers in unison by contacting the loop provided carrier when the pull-cords have been released, and means for anchoring the pull-cords to hold the carriers in contact with the aforesaid elements.

3. A curtain raising and lowering fixture embodying apertured members adapted to be secured to the upper end of a window frame adjacent the corners thereof, a pair of flat plate like carriers adapted to support telescopically connected curtain supporting sections, a pair of pull-cords from which the carriers are suspended below said apertured members, one of said cords being supported by both of the apertured members, the other cord being supported by only one of the apertured members, cord receiving loops carried by one of the plate like carriers through which both pull-cords pass downwardly, an adjustable spacer secured to the pull-cords at a selected position below the loop provided carrier to limit downward movement of the carriers, and the apertured members limiting upward movement of the carriers by coming into end contact therewith when in their extreme raised position.

4. The combination, in a curtain raising and lowering fixture, of a pair of apertured members adapted to be anchored adjacent the upper corners of a window frame, one of the members having a single vertical passage and the other member having two spaced vertical passages, a pair of pull-cords, one of the pull-cords riding in passages in both members and the other pull-cord riding in the member having the single passage, carriers suspended from each cord below the said members, said members also serving as stops to limit upward movement of the carriers, loops carried by one of the carriers for guiding the pull-cords in suitable spaced relation, and a spacer carried by the pull-cords below the loop provided carrier for limiting downward movement of the carriers, and telescopically connected curtain-rods connected at their outer ends to the carriers.
